(57) **CLAIM**

The ornamental design for extrusion die plate, as shown and described.

DESCRIPTION

FIG. 1 is an upper perspective view of an extrusion die plate or sieve according to our design.

FIG. 2 is a top view of the extrusion die plate.

FIG. 3 is a bottom view of the extrusion die plate.

FIG. 4 is an elevational side view of the extrusion die plate, with the extrusion die plate being symmetrical about its periphery; and,

FIG. 5 is a perspective view showing the extrusion die plate mounted to establish a food dispensing port in a flexible container.

The dotted lines depicting a flexible body container in FIG. 5 is presented for environment only and is not part of the claimed invention.
